UNITED STATES PATENT OFFICE.

JOHN H. TURCOTTE, OF INDIAN ORCHARD, MASSACHUSETTS.

SADDLE FOR SPINNING-FRAMES.

No. 877,020.

Specification of Letters Patent.

Patented Jan. 21, 1908.

Application filed August 7, 1907. Serial No. 387,439.

To all whom it may concern:

Be it known that I, JOHN H. TURCOTTE, a subject of the King of Great Britain, residing at Indian Orchard, in the county of Hampden and State of Massachusetts, have invented certain new and useful Improvements in Saddles for Spinning-Frames, of which the following is a specification.

My invention relates to improvements in saddles for the upper rolls of spinning frames for cotton, silk, etc., at the top, in which the main saddle is constructed with an oil conduit which receives its supply or is filled from behind the clearer-board and from 10 which the oil is delivered to the bearing points through openings or passages leading from such conduit and opening over such points for the purpose of lubricating the bearing surfaces; said improvements also 15 embrace, in addition to the aforesaid features, a certain peculiar auxiliary or bottom saddle, and means to lock the main saddle and blade together, all as hereinafter set forth.

20 The objects of my invention are, first, to produce a simple and durable saddle of the character mentioned above, which is adapted to receive and contain oil and to distribute the oil directly to the different bearing points 25 in such a manner that they will be lubricated uniformly, abundantly, and properly, without waste; second, to afford convenient means for easily and quickly filling the conduit in the saddle with oil without removing 30 the clearer-board; third, to avoid all danger of spilling oil on the rolls and so spoiling those which are covered with leather, the front rolls, on the one hand, and soiling or ruining the roving, on the other hand; fourth, 35 to so construct the lower saddle that there shall be no escape of oil laterally therefrom; fifth, to provide means for locking together, as it were, the main saddle and the weighted blade which holds it down to its work, where- 40

45 by neither one nor both is or are liable to get lost, as frequently happens with those now in common use, and, sixth, to furnish a self-closing cover at the entrance to the oil conduit so as to keep out dust and dirt.

50 In spinning frames for fine thread where the speed is slow no lower or under saddle is employed.

I attain the above-mentioned objects by the means illustrated in the accompanying 55 drawings, in which—

Figure 1 is a sectional view of assembled parts which embody my invention and illustrate a practical application of the same; Fig. 2, a rear end view of the two saddles shown in the preceding view, without the cap; Fig. 3, 60 a front elevation of the part of the blade which has the eye therein to receive the main saddle, and, Fig. 4, a sectional view similar to the first except that here the under saddle is omitted and there are only two bearing points and oil outlets for the same number of journals.

Similar figures refer to similar parts throughout the several views.

In Fig. 1 three rolls 5 are represented, with 70 two saddles 6 and 7 bearing on the journals 8 of such rolls to hold the latter down forcibly on the same number of bottom rolls 9, a weight 10 suspended from a blade 11 supported from said saddle 6 affording the 75 required amount of pressure. A clearer-board is represented at 12, the same resting on the saddle 6. In Fig. 4 the same elements are shown with the exception of the under saddle and one pair of rolls 5 and 9. It is to 80 be understood that, in practice, the roving passes between the rolls 5 above and the rolls 9 below. The arrangement of the members just pointed out and their relation to each other are generally old and well known, but 85 the construction of the saddles is new and novel and will now be described, beginning with the main saddle which is employed in every case. This saddle, 6, is provided with an upstanding extension or arm 13 at the 90 back end, rising behind the clearer-board 12 when the parts are assembled, as they are assumed to be for the purposes of this description. Said saddle is hollow, that is, it has a comparatively large passage or conduit 95 14 therein which opens through the top of the arm 13 and from which small openings or passages 15 extend to open through the bottom of the horizontal part of the saddle either directly onto the journals 8 or into the 100 saddle 7 when the latter is present.

Passing next to the saddle 7, it will be noticed that the upper surface thereof is dished to form a shallow receptacle or recess 16 in the top below the middle and rear passages 15 in the main saddle, and that this recess communicates with the two journals 8 below by way of two small openings or passages 17 which open through the bottom of said saddle 7 directly onto said journals. By 110

preference the recess 16 is filled with a mass 18 of wicking or other suitable absorbent material.

The saddle 7 is made somewhat wider than 5 the saddle 6 and is provided with flanges 19—19 between which said saddle 6 is received. These flanges rise from the saddle 7 on both sides of the recess 16 and prevent the oil from leaking out laterally between the two saddles 10 and so wasting and fouling the rolls and roving.

More or less than two passages 15 may be provided in the saddle 6 to open into the recess 16; and should there be more than two 15 journals under the saddle 7 there must be an increased number of passages 17.

The blade 11 has an eye 20 at the top to receive the saddle 6, by which said blade and its weight 10 are supported, but the front 20 terminal of said saddle is larger than such eye and this precludes the possibility of either taking the blade off of the saddle over the front end of the latter or of moving the saddle backward out of engagement with the blade. 25 And by placing a cap 21 on the arm 13, as shown, which is too large to pass through the eye 20, I provide against the separation of the saddle 6 and the blade at the back end of the former while said cap is in place. Thus 30 it will be seen that there is no liability of accidental separation of the saddle 6 and the blade and consequent trouble and loss. The angular or bent, back part of the saddle 6, however, is small enough to pass through the 35 eye 20, in the absence of the cap 21, and so permit said saddle and blade to be connected and disconnected in this way, said cap being removable at will. It is obvious too, that while the clearer-board 12 is in front of the 40 arm 13 said clearer-board prevents the removal of the connected saddle and blade. The clearer-board and the saddle 6 are indented, as shown in Figs. 1 and 4, to receive and engage the head of the blade.

45 The cap 21, which is screwed on to the upper terminal of the arm 13 in the present instance, has a lid or cover 22 pivoted thereto at 23 and provided with a lug 24 at the back which is designed to encounter the adjacent 50 portion of said cap, when said cover is opened, to prevent the latter from being raised to a point where it will not immediately drop down and close itself as soon as it is released. The cover 21 is shown in its most elevated 55 position by dotted lines in Fig. 1, and from this it will be seen that said cover must close of its own weight upon being released. A cover of this kind cannot become detached and lost and it renders the saddle with which 60 it is connected dust-proof. It is true that the cover must be held open while filling the conduit, but since the filling is accomplished very quickly the necessity of holding up the cover is not a serious disadvantage at all.

65 The conduit 14 is filled with oil from time

to time as may be required, and the oil in said conduit runs slowly through the passages 15 and 17, which should be very small indeed, onto the journals 8, whereby said journals and the saddle bearing surfaces are kept 70 lubricated continually and will not run dry so long as there is oil in the conduit. The oiling or lubricating is done automatically and there is no chance of getting oil on parts where it is not wanted or where it would be 75 likely to do damage. The saddle 7, which is used except as hereinbefore noted, transfers oil to the journals upon which it bears, from the main saddle, through the medium of the wicking 18 which receives the oil from the 80 two passages above and delivers it or permits it to be delivered through the passages 17. In the absence of the saddle 7, as in Fig. 4, the oil passes directly to both journals. The conduit 14 is usually large enough to hold a 85 sufficient amount of oil to last several days.

The advantages of having the filling hole or entrance to the oil conduit at the upper end of the arm 13, which is behind the clearer-board 12, have already been pointed 90 out.

If the passages 15 become stopped up, they can be freed easily from obstructions, when the saddle 6 is detached from the machine, by inverting the saddle and inserting 95 a pin or fine wire in such passages, after which the matter thus dislodged and forced into the conduit is shaken out of the open end of the latter in the end of the arm 13.

The two saddles, that is, the main saddle 100 and the under saddle, can be constructed to apply to or be used in connection with more than three journals in a row, but ordinarily there are no more than that number of journals employed in machines of this kind.

The cap 21 with its cover 22 may be omitted if desired, some other means, an ordinary stopper for example, being substituted as a closure for the entrance to the conduit 14, unless it shall be concluded to 110 leave such entrance open; furthermore, various changes in shape, size, and minor details of construction may be made without departing from the nature of my invention.

What I claim as my invention, and desire 115 to secure by Letters Patent, is—

1. As an improved article of manufacture, a saddle for spinning frames consisting of an approximately horizontal part having bottom perforations and of an upstanding arm, 120 such part and arm having an inclosed angular oil conduit or passage therein which is closed at its front terminal, extends from a point near the forward end of said approximately horizontal part longitudinally 125 through such part and upward through said arm, and opens through the arm and through said perforations in the bottom of the horizontal part.

2. The combination, in a spinning frame, 130

- with a set of upper roll journals, of a saddle comprising a part which is adapted to bear on such journals and an upstanding arm, such saddle having an inclosed angular conduit or passage therein opening at intervals through smaller passages in the bottom thereof, the receiving end of such angular passage being in said arm, and a second saddle adapted to be interposed between the first saddle and certain of said journals and arranged to receive oil from the main passage through certain of the smaller passages in said first mentioned saddle and to deliver it to the journals below.
3. The combination, in a spinning frame, with a set of upper roll journals, of a saddle comprising a part which is adapted to bear on such journals and an upstanding arm, such saddle having an inclosed angular conduit or passage therein opening at intervals through smaller passages in the bottom thereof, the receiving end of such angular passage being in said arm, and a second saddle adapted to be interposed between the first saddle and certain of said journals and arranged to receive oil from the main passage through certain of the smaller passages in said first saddle and to deliver it to the journals below, said second saddle having flanges at the sides only to embrace the first saddle.
4. The combination, in a saddle for spinning frames, with an approximately horizontal part having bottom perforations, and an upstanding arm integral with said approximately horizontal part, such part and arm having an inclosed angular oil conduit or passage therein which is closed at its front terminal, extends from a point near the forward end of the approximately horizontal part longitudinally through such part and upward through said arm, and opens through the latter and through said perforations in the bottom of the aforesaid horizontal part, of a self-closing lid on the arm at the entrance to said passage.
5. The combination, in a spinning frame, with a set of upper roll journals, and a weighted blade having an eye therein, of a saddle adapted to bear on or to be supported by said journals and in turn to support such blade, said saddle comprising an approximately horizontal part with an integral upstanding arm at the rear end, the front terminal of said approximately horizontal part being larger than the eye in said blade, but the back portion of the saddle including the arm and the angle or elbow being small enough to pass through such eye.
6. The combination, in a spinning frame, with a set of upper roll journals, and a weighted blade having an eye therein, of a saddle adapted to bear on or to be supported by such journals and in turn to support such blade, said saddle comprising an approximately horizontal part with an integral upstanding arm at the rear end, the front terminal of said approximately horizontal part being larger than the eye in said blade, but the back portion of the saddle including the arm and the angle or elbow being small enough to pass through such eye, and a removable cap on said arm which is also larger than said eye.
